Patented Sept. 29, 1959

186,211

VACUUM CLEANER CASING

Herbert J. Allemand, Bloomington, Ill.

Application August 4, 1958, Serial No. 52,046

Term of patent 7 years

(Cl. D9—2)

Fig. 1.

Fig. 2.

Fig. 3.

Fig. 4.

Figure 1 is a perspective view of a vacuum cleaner casing embodying my new design;

Figure 2 is a side elevational view thereof;

Figure 3 is an end elevational view thereof; and

Figure 4 is a bottom plan view thereof.

The essential features of my design are shown in full lines.

I claim:

The ornamental design for a vacuum cleaner casing, substantially as shown and described.
